UNITED STATES PATENT OFFICE.

ARTHUR HOUGH, OF DRAGON, QUEBEC, CANADA.

CONDENSER.

1,291,893.

Specification of Letters Patent.

Patented Jan. 21, 1919.

Application filed July 15, 1916. Serial No. 109,591.

To all whom it may concern:

Be it known that I, ARTHUR HOUGH, of Dragon, in the Province of Quebec, Dominion of Canada, a subject of the King of Great Britain, have invented certain new and useful Improvements in Condensers; and I do hereby declare that the following is a full, clear, and exact description thereof.

My invention relates to condensing systems and more particularly to systems of the multiple condenser type; and it may be said briefly to consist of a condenser unit adapted to present a plurality of condensing members affording relatively large condensing surfaces, each member being constructed and arranged to have the cooling medium pass through the same in one direction only in contradistinction to the prevailing method of causing the current to flow in a zig-zag or circuitous path through the unit. The effect is that in my condenser there is uniformity of temperature throughout each level in a unit containing a multiplicity of members, whereas, in the condensers heretofore used a considerable variation in temperatures occurs throughout each level owing to the fact that the condensing medium is made to pass through different levels more than once and each time its condensing efficiency is lessened. For full comprehension, however, of my invention reference must be had to the accompanying drawings in which similar reference characters indicate the same parts, and wherein:

Figure 1 is a side elevation partly in section of a condenser unit constructed according to my invention, the section being taken on line 1—1 Fig. 3;

Fig. 2 is a transverse sectional view taken on line 2—2 Fig. 1;

Fig. 3 is a plan view;

Fig. 4 is a part plan part sectional view with the condensing members removed;

Fig. 5 is a vertical sectional view of one of the condensing members; and

Fig. 6 is a vertical sectional view taken on line 6—6 Fig. 1 and illustrating the trap in elevation.

I have illustrated my invention applied to an apparatus for condensing nitric acid although it may be utilized for other condensing operations, without departing from the spirit of my invention.

In order to resist the action of such acids as nitric I prefer to make all its parts of a high ferro-silicon mixture.

The condenser body, or container 2, is oblong in plan view and slightly upwardly flared, with shoulders 3 and 4 at its top and bottom to support top and bottom plates by which my improved condenser members are carried and holes 10 and 12 for connection of the fume pipes (not shown).

The bottom plate, indicated at 5, conforms to the bottom of the container or body 2 and has preferably seven rows of four holes 6 beveled to serve as seats for the condenser members; while between these rows of seats are series of ports 7 through which the condensed acid finds its way to the outlet 8 of the condenser.

The top plate is divided into as many parts, 20, as there are rows of condenser members. They rest on the shoulders 3 and have holes 12 for the condenser members to pass through, the holes being in vertical alignment with the seats 6 and adapted to space the members and retain them in vertical position.

The condensing members are an important feature of this invention and consist of straight tubes 25 of relatively large bore having their lower ends closed and rounded and their upper ends formed with mouths the lips 26 of which extend horizontally. These tubular members are inserted through the top plates and seated in the bottom plate and disposed with their lips overhanging and communicating with a pair of troughs 28 and 29 supported on brackets fastened to the top of the container.

The condensing medium, water in this case, is supplied to the bottom of these condenser members and overflows from them into the troughs and thence to waste. According to the present embodiment of my invention a series of tubes 30, preferably glass, are located in the members by being suspended by rubber tubing 31 from pipes 32 connected to and supplied by headers 33 fed from any available supply through T-connections 34. In order that the temperature of the condensing medium may be approximately the same throughout the full length of each member, the fresh supply is made to enter the latter at the bottom from the feeding tube. To secure a slowly flowing and comparatively large condensing body with, in consequence, a relatively high condensing potentiality, the tubes 30 are of small bore, thus presenting greater space for the liquid within the members, and they ex-

tend down within the members to within close proximity of the bottom thereof.

The run-off for the nitric acid consists of a pair of traps 8 and 9 one below the floor 5 and the other on a level with the same. Each of these traps is provided with a port 50 for cleaning purposes.

This cleaning port is of great value in that it allows removal of sediment without stopping the operation of the condenser.

Operation.

In the operation of my improved multiple system condenser the fumes pass through the 15 same from the pipe connection 10 to the pipe connection 12 and impinge upon the condenser members during their passage. These condenser members are all maintained at the same temperature by the fact that the 20 water serving as the condensing medium is conducted to the bottom of each member and moves slowly upwardly therein, flowing into the troughs; while efficiency is comparatively high each member being of straight 25 tubular form, vertically arranged and of relatively large diameter the effect being that the aggregate cooling surface within the condenser is relatively large. Thus the condensing efficiency is high and practically 30 uniformly maintained throughout the unit.

What I claim is as follows:—

1. In a condenser unit for nitric acid vapor comprising a container, a bottom plate spaced from the bottom thereof and a series 35 of transverse top plates serving as a cover for the container, the bottom plate having seats and intervening holes communicating with the bottom space and the top plates

having openings; a series of condenser members of straight tubular form with closed 40 lower ends and lateral discharge mouths at their upper ends, said condenser members being inserted through the openings in the top plates and seated in the bottom plates; tubes located within the members and extending from a short distance from the bottom thereof to a point above the mouth; headers at the sides of the container; pipes connecting the headers to the tubes.

2. In a condenser unit for nitric acid 50 vapor comprising a container; a bottom plate spaced from the bottom thereof and a series of transverse top plates serving as a cover for the container, the bottom plate having seats and intervening holes communicating with the bottom space and the top plates having openings, a series of condenser members of straight tubular form with closed lower ends and lateral discharge 55 mouths at their upper ends, said condenser members being inserted through the openings in the top plates and seated in the bottom plates; glass tubes located within the members and extending over a short distance 60 from the bottom thereof to a point above 65 the mouth; headers at the sides of the container; pipes connecting the headers to the tubes, such pipes including readily detachable flexible connections.

In testimony whereof I have signed my 70 name to this specification in the presence of two witnesses.

ARTHUR HOUGH.
